UNITED STATES PATENT OFFICE

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND

RING TRAVELER

Application filed March 21, 1929. Serial No. 348,845.

My invention relates to ring travelers for spinning and twisting machinery.

It is necessary for practical use that a ring traveler have such a degree of elasticity or resiliency as to permit ample distention of the ends to pass over the shoulders of the ring without breaking, and upon release, engage thereunder. On the other hand if the mass of metal in the traveler is of such thickness as to prevent adequate tempering of the same, the metal has then to be left sufficiently soft or pliable as to permit the traveler to be bent and rebent in applying the same to the ring, with the result that the traveler in use will often bend and escape from the ring, and invariably the softness of the material of the traveler causes quick destruction by speedy and excessive wear.

It has been attempted to overcome the indicated disadvantages by forming the traveler from a length of material arcuate in cross section, that is to say, from a length having a rounded inner face and a flat outer face. This form was found impractical, however, because of the excessive amount of metal present in the rounded portion, and furthermore because it made bending the stock into final form difficult, and massed the material in an intermediate portion of the traveler where its presence still further increased the lack of flexibility.

The objects of my invention are to overcome the disadvantages above adverted to, as well as the usual purposes of preventing air resistance to the movement of the traveler, and wear or cutting of the yarn in its movement through the traveler.

My invention consists in forming the traveler with plane parallel inner and outer faces and inclined, sloping, or beveled lateral faces.

In the accompanying drawings which form a part of this specification

Figure 1 is a perspective view of a ring traveler of the "horizontal" type used on spinning machinery and embodying my invention,

Figure 2, a similar view of the metal blank from which the traveler shown in Figure 1 was formed,

Figure 3, a transverse section of the traveler taken on line 3—3 of Figure 1,

Figure 4, a side elevation of a ring traveler of the "vertical" type used on twisting or doubling machinery embodying my invention, and

Figure 5, a section taken on line 5—5 of Figure 4.

Like characters of reference indicate like parts throughout the views.

In carrying out my invention I utilize a straight strip or oblong bar of relatively soft metal, indicated in a general way by 8, and shown in Figure 2. In detail this comprises outer and inner broad plane parallel faces 9 and 10, the former of greater width than the latter. The sides or edges of the strip are parallel inclined, beveled, or sloping surfaces 11.

In forming a horizontal traveler 12 the strip is by suitable tools bent into the form shown in Figure 1 which comprises the arch or body portion 13 and the horns or ring engaging ends 14. The broader plane face 9 of the strip 8 constitutes the outer surface of the traveler. The traveler is completed by tempering.

In forming a vertical traveler 16 the strip 8 is bent into the form shown in Figure 4 with the broader face 9 of the strip 8 upon the outer surface of the structure. Herein 17 represents the arch or intermediate portion, and 18 the ring engaging ends. This traveler is tempered as usual after bending.

In both forms of travelers it will be observed that the plane character of both the inner and outer faces not only facilitates the bending of the material at the junction of the body and ring engaging ends and elsewhere, but that the parallel relation of the plane faces 9 and 10 produces a uniformity of thickness throughout the structure that permits facile, thorough, and uniform tempering.

It will be noted also that the beveled or inclined shape of the lateral edges throughout the traveler structures affords a facile and non-abrasive bearing for the passage of the yarn thereover, and presents a minimum

of resistance to the air during the movement of the traveler.

I claim:—

1. A ring traveler having parallel inner and outer faces, the width of the traveler increasing from each edge of the inner face toward the corresponding edge of the outer face.

2. A ring traveler having parallel inner and outer faces each of uniform width throughout, the width of the outer face being greater than that of the inner face, the traveler having an inclined portion extending from each edge of the inner face toward the corresponding edge of the outer face.

In testimony whereof I have affixed my signature.

GEORGE H. GILLIGAN.
